UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

WORK CLAMP FOR SEWING MACHINES.

Application filed December 7, 1925. Serial No. 73,705.

- This invention relates to work clamps for sewing machines and particularly to work clamps for use with sewing machines of the so-called "tacker" type, that is, sewing machines which are designed to insert short reinforcing seams in garments, such for instance as the bar at the end of a buttonhole or the tack or reinforcing seam at the corners of pockets, etc.
- 10 One of the objects of the present invention is to provide a novel work clamp which is constructed to afford ample room to receive the garment or other work in which the reinforcing seam is to be placed.
- 15 In the sewing of these reinforcing seams in a garment it frequently happens that the location of the place to be reinforced is such that in order to arrange the garment in proper position to receive the reinforcing seam it is necessary to place a considerable amount of cloth in the rear of the sewing point. The work clamp which forms the basis of the present invention is designed to provide sufficient room for this purpose.
- 20 Other objects of the invention are to improve generally work clamps in various particulars all as will be more fully hereinafter described and then pointed out in the appended claims.
- 25 In the drawings wherein I have shown a selected embodiment of my invention, Fig. 1 is a side view of a portion of a sewing machine having my improvements applied thereto;
- 30 Fig. 2 is a front view of the work clamp; Fig. 3 is a section on the line 3—3, Fig. 1; Fig. 4 is a top plan view of the work clamps.
- 35 In Fig. 1 I have shown at 1 a portion of the frame of a sewing machine, said frame having the overhanging arm 2 in the end of which is mounted for vertical reciprocation, the usual needle bar 3 carrying the upper needle 4. The frame 1 also is provided with a laterally-extending work-supporting arm 5 on which the work 6 is supported.
- 40 The sewing machine herein illustrated is similar to that shown in my co-pending application Serial No. 58,246, filed September 24th, 1925, to which reference may be made.
- 45 During the sewing operation the work 6 is clamped between an under work-clamping member 7 and upper work-clamping members 8. These upper and under work-clamp-
- ing members are mounted on and carried by a rigid frame or support indicated generally at 9. Said support is formed with a foot or base portion 10 which overlies the arm 5 and to which the under work-clamping member is secured and it is also formed with the vertically-rising standard 11 having the forwardly-extending portion 12. The upper work clamp 8 is supported by the up-standing portion 11 of the frame, as will be presently described.
- 50 The frame or support 9 as a whole is pivotally mounted to the arm 5 as shown at 13 so as to permit the work clamps to have the vibrating motion necessary to form the tacking stitches.
- 55 The upper work clamp 8 comprises two members 14 and 15, each having a horizontal clamping foot 16 which rests on the work, a vertical portion 17 and a rearwardly-extending portion 18. Each section or part 60 of the upper work clamp 8 is carried by a lever 19, the forward end of which is secured to the portion 18 of the work clamp section and which extends rearwardly to the rear end of the frame and the rear end of which is bent downwardly as shown at 20. The downwardly-bent rear end of each arm 19 is pivotally connected to the up-standing portion 11 of the frame as shown at 21. The two sections of the upper work clamp 8, 65 therefore, are supported to turn about the pivot 21 as an axis.
- 70 The upper work clamp 8 is supported to turn about the pivot 21 as an axis.
- 75 The upper work clamp 8 is supported to turn about the pivot 21 as an axis.
- 80 The upper work clamp 8 is supported to turn about the pivot 21 as an axis.
- 85 The upper work clamp 8 is supported to turn about the pivot 21 as an axis.
- 90 The upper work clamp 8 is supported to turn about the pivot 21 as an axis.
- 95 The upper work clamp 8 is supported to turn about the pivot 21 as an axis.
- 100 Each arm 19 is acted on by a spring which operates to hold the corresponding clamp member yieldingly against the work. These springs are indicated at 23, each spring being in the form of a U spring and having one end bearing against the upper side of the arm 19 and the other end in engagement with the under side of a projection 24 carried at the end of the forwardly-extending portion 12 of the frame. A guide is also provided for guiding the arms 19 in their

swinging movement. This guide is indicated at 25 and it is also secured to the end of the forwardly-extending portion 12 of the frame. The guide is formed with two slots 26 open at the bottom and in which the arms 19 are received. This guide 25 holds the arms from lateral movement when the clamp is opened and closed.

Means are provided for manually opening the clamps by raising the upper work clamp 8. For this purpose I have provided a lever 27 which is pivoted centrally at 28 on the under side of the overhanging arm 2, the rear end of the lever having a link 29 connected thereto which leads to a suitable treadle. The front end of the lever has pivotally secured thereto a lifting member 30 which has a general inverted T shape, the shank of the member being received between the arms 19 and the lower end of the member being formed with lateral extensions 31 which are situated underneath the arms 19.

When the treadle is depressed thereby pulling the rear end of the lever 27 downwardly the resultant upward movement of the front end of said lever will bring the projections 31 against the under side of the arms 19 and will thereby raise said arms as shown by dotted lines Fig. 1. This will elevate the upper work clamp 8 so as to permit the work to be either placed in the clamps or removed therefrom.

The work clamp is simple in construction and yet it affords ample room to accommodate a large amount of material thus making it easy for the operator to manipulate the garment for the insertion of the reinforcing seams.

I claim:

1. In a sewing machine, the combination with a frame having a work-supporting portion, of a work-clamp-supporting member provided with a base portion secured to the work-supporting portion of the frame and also provided with an up-standing portion which is provided with a forward extension, a lower work clamp secured to the forward end of the base portion, arms pivoted to said up-standing portion and extending forwardly beyond the forward extension, upper clamping members carried by the forward end of said arms and springs carried by said forward extension and acting against the arms

to hold the upper clamping members yieldingly against the work.

2. In a sewing machine, the combination with a frame having a work-supporting portion, of a work-clamp-supporting member provided with a base portion secured to the work-supporting portion of the frame and also provided with an up-standing portion, a lower work clamp secured to the forward end of the base portion, horizontally-extending arms each having its rear end bent downwardly and pivoted to the up-standing portion of the supporting frame, and upper work clamps carried by the forward end of said arms.

3. In a sewing machine, the combination with a frame having a work-supporting portion and an overhanging arm, of a work clamp-supporting frame presenting a base portion resting on and secured to the work-supporting portion of the frame and also having an up-standing portion, a lower work clamp secured to the front end of the base portion, horizontal arms pivotally secured to the up-standing portion of the work clamp support, upper work clamp members secured to the forward end of said arms, a manually-controlled lever pivoted to the under side of the over-hanging arm of the frame, and a connection between said lever and said arms whereby the work clamps may be opened by rocking the lever.

4. In a sewing machine, the combination with a frame having a work-supporting portion and an overhanging arm, of a work clamp-supporting frame presenting a base portion resting on and secured to the work-supporting portion of the frame and also having an upstanding portion, a lower work clamp secured to the front end of the base portion, horizontal arms pivotally secured to the upstanding portion of the work clamp support, upper work clamp members secured to the forward end of said arms, a manually-controlled lever pivoted to the under side of the over-hanging arm of the frame, and a lifting member pivoted to the front end of said lever and having projections underlying said arms, whereby when the lever is rocked the work clamp will be opened.

In testimony whereof, I have signed my name to this specification.

JOHN KIEWICZ.
